STRAND PACKAGING APPARATUS

Albert E. Winslow, Norwich, Conn., assignor, by
mesne assignments, to Farrel-Birmingham
Company, Incorporated, Ansonia, Conn., a cor-
poration of Connecticut

Application January 11, 1944, Serial No. 517,861

5 Claims. (Cl. 242—35.5)

This invention relates to an apparatus for packaging strand material and deals specifically with a unit in a thread finishing apparatus which is the subject of my co-pending application Serial No. 517,862, filed January 11, 1944.

In a strand or packaging machine where the size of the package is increasing a friction drive which slips to compensate for growing size of the package is usually utilized for driving the package for taking up the strand material. Such a slip is in many instances unsatisfactory and does not permit of the desired tension being applied to the strand material. Difficulties in such packaging are multiplied when a large number of packages are to be handled.

One of the objects of this invention is to provide a packaging machine or take-up machine for strand material through which a large number of packages may be handled and the strand material delivered to each of the packages under the desired tension.

Another object of this invention is to provide a drive for a strand package so that no slip will occur in the drive while the package is increasing in size.

A more specific object of this invention is to provide a surface drive for a plurality of the packages and yet such a surface drive as will be simple and may be operated with a minimum amount of trouble.

Another object of this invention is to balance the traverse mechanisms so that they will be easily operated.

With these and other objects in view, the invention consists of certain novel features of construction, as will be more fully described and particularly pointed out in the appended claims.

In the accompanying drawings:

Fig. 1 shows a fragmental portion of the machine at the head end partly in section to illustrate the drive;

Fig. 2 is a vertical section through the machine adjacent one of the upright supporting frames;

Fig. 3 is a horizontal section illustrating the drive for the traverse bars;

Fig. 4 is a section on line 4—4 of Fig. 3;

Fig. 5 is a diagrammatic view in plan illustrating the transmission of movement to the traverse mechanism;

Fig. 6 is a plan view illustrating a means for tensioning the driving belt;

Fig. 7 is a detailed sectional view illustrating the mounting of a spindle for receiving the package spool and also illustrating the driving belt for this spool;

Fig. 8 is a plan view of the parts shown in Fig. 7;

Fig. 9 is a diagrammatic view illustrating in plan the arrangement of the driving belt for the packages and the supporting and tensioning means therefor;

Fig. 10 is a diagrammatic view illustrating the delivery of the strand material to the different packages;

10 In proceeding with this invention I provide a suitable framework for supporting a plurality of rows of packages for the reception of strand material. A belt extends in a vertical plane along each row of packages so that the packages will contact therewith and be driven by the belt, thus providing a surface drive for each package. A long bar with guides adjacent each package is provided and this bar is traversed to lay the strand material on the package as desired. I provide even numbers of rows of packages and guides therefor and I so traverse the thread guides that the motion of any pair is one opposite the other so that as one of the bars is going up the other bar is going down whereby 15 the bars may be arranged in balanced relation.

With reference to the drawings I have shown in Fig. 2 an upright supporting frame designated generally 10 which is arranged with suitable legs 11, 12 with a vertical post 13 and an inclined support 14 in order that a stepped arrangement of packages may be provided. One of these frames will be at each end of the machine while one or more may be intermediate the ends depending on the length of the machine to be provided.

20 The several structures 10 are tied together by hollow rods arranged in pairs as at 15 and 16 at the back and hollow rods 17 and 18 at the front which are bound to the frame structures 10 to provide a rigid framework. Additional rods 15a and 16a and 17a and 18a are provided, there being as many of these tie rods as there are to be rows of packages arranged on the frame. In this case I have illustrated four and the other two sets of tie rods are designated respectively 25 as 15b, 16b, 17b, 18b, and 15c, 16c, 17c, and 18c.

At suitable intervals along these rods such as 17 and 18 brackets as 20 (see Fig. 8) are provided which are clamped to the rods and are equipped with a spindle 21 for rotatably supporting a back-up guide 22 thereon. These guides are in horizontal alignment. Other similar guides 22a, 22b, and 22c, are similarly arranged on the rods with the a, b, and c exponents respectively. A belt 24 which is substantially the width of the 30 guide 22 extends along and in engagement with 35

the guides 22 and thence around a terminal guide 25 and 26 and around the driving drum 27 (see Fig. 9). Similar belts 24a, 24b, and 24c, extend along the guide 22a, 22b, and 22c, respectively and around similar end guides as shown at 25 and 26 and also about drive pulleys 27a, 27b, and 27c respectively as shown in Fig. 1.

In order that this belt 24 or the other belts 24a, 24b, and 24c may be tensioned I have provided for engagement with each belt at suitable intervals along its extent between the guides and drives 26 and 27. The belt 24 is engaged to tension it by a pulley 29 which is mounted on a lever 30 pivoted in a bracket 31 attached to the rods 15 and 16. This lever is pulled in a direction to force the pulley outwardly into engagement with the belt to tension the same by means of a flexible element 32 directed over a sheave 33 mounted on a bracket 34 and weighted as at 35. Similar parts with the exponent *a*, *b*, and *c* are indicated for the different rows which are characterized by these exponents.

On the rods 17 and 18 I have also provided a bracket 36 (see Fig. 8) which supports a stud 37 about which an arm 38 is swung by means of a spring 39. This arm has mounted in it a spindle 40 upon which a package spool 41 is rotatably mounted. The package spool has heads 42 and 43 a distance apart sufficiently so as to receive the driving belt 24 between these heads. The belt engages the barrel 44 of this spool so as to rotate the same and as the strand material is accumulated thereon it engages the surface of the strand material providing a surface drive therefor. The spring swings the arm of the spindle toward the belt to provide the desired frictional drive necessary while as the package builds up by the accumulation of strand material thereon the arm will swing away against the spring pressure which is provided. The brackets 36 are adjustable along the rods 17 and 18 and position a package at about the mid point on the belt between its contacts with the supporting guides 22.

A traverse bar 45 carrying strand guides 46 at intervals along its length opposite each of the packages is supported by a post 47 at each of the upright supporting frames which posts are guided in the bearings 48 and 49 provided in the frame while each of the posts is equipped with a foot 50 to rest upon the roll 51 of a lever arm 52 (see Fig. 1) which rock so as to vertically move the post 47 through its bearing to traverse the strand on the package.

The main drive shaft 28 is vertically located at the head end of the machine and is driven (see Figs. 1 and 3) by means of a worm gear 55 and worm 56 on shaft 57 is driven by the belt pulley 58. This shaft 57 is mounted in a sleeve 59 and bracket 60 which may be moved about the center of the shaft 28 through an arc so that drive from the desired direction may be easily had. The traverse drive is taken off this shaft 28 by means of gear 61 fixed thereon meshing with a gear 62 having a gear 63 which is secured to rotate therewith and which in turn meshes with a gear 64 on the shaft 65. This shaft 65 carries a worm 66 (Fig. 1) which meshes with the gear 67 on shaft 68, which shaft carries the heart shaped cam 69 to engage the follower 70 on the end 71 of the bell crank arm whose other arm 72 is connected by the link 73 with the arm 74.

A rod 76 is also attached to the arm 74 which transfers motion to an arm 74x associated with the next upright support frame and to an arm

74y at the end support frame of the machine. A sectional shaft having one part 75 telescoping another part 75' is supported in bearings 77 and 78. The arm 74 is fixed to the part 75 which also has fixed to it arms 52 and 52a so that as the arm 74 is rocked the arms 52 and 52a are also rocked about the axis of the shaft 75. The reduced portion 79 of the shaft 75 fits into the tubular portion 75' which is free to rotate about this portion 79. Arms 52b and 52c are fixed on the portion 75' as is also a depending arm 80.

At the opposite end of the machine there is a similarly arranged sectional shaft with one part 81 telescoping another part 81'. The arm 74y is attached to the part 81 which carries arms 52cy and 52by while the part 81' is free to rotate about a reduced portion of the part 81 and carries arms 52y and 52ay, also an upwardly extending arm 82.

A solid shaft 83 is at the mid-stand of this frame and is rocked by the arm 74x which is fixed thereto. This shaft 83 carries arms 52x and 52ax on one side and 52bx and 52cx on the other side while upwardly extending from one part of the arm is an arm 84 and downwardly extending from another part of the arm is an arm 85. The arms 84 and 85 are provided with suitably arched surfaces to engage a steel band for driving the telescoping portions of the shaft 75' and 81'. Thus the steel band 86 drives from the arms 84 to the arm 80 to rock the part 75' and arms 52b and 52c thereon while the steel band 87 drives from the arm 85 to the arm 82 to rock the arms 52y and 52ay. The arrangement of these steel bands is such that they produce upward motion of the arms which they operate while the weight of the supporting posts and the guide rails are sufficient to follow these arms downwardly when they are permitted to move downwardly by rocking motion of the center shaft 83. In this manner as the two arms 52 and 52a, or the arms 52x and 52y with exponents *a* and *b* are moving in one direction, the arms 52b and 52c and the arms 52x and 52y with exponents *c* and *d* are moving in the opposite direction whereby a balanced arrangement of motion is provided for.

The operation of the several elements of the apparatus has been given in connection with the detailed description thereof. Therefore, a general description of the operation of the apparatus as a whole will suffice in order to clearly understand its mode of operation.

A spool 41 is placed on the spindle 40. An individual strand is then led to the barrel of the spool and secured thereto in any well known manner such for instance as wrapping the strand about the barrel thereof. The spring actuated spindle holder is then allowed to move the spool into contact with the particular belt associated therewith. The winding of the spool then commences and is continuous until the spool is filled and removed from the apparatus, the traverse bar properly guiding the strand in a well understood manner. It is of course to be understood that there is a multiplicity of spools and motion above described in each apparatus. The strand may be led to the spool from a suitable supply. In the instant case a plurality of strands previously treated in an apparatus designated generally 181, see Fig. 10, are led therefrom as at 180 to a common guide. From this common guide the strands are led individually to individual guides 46 carried by the traverse bars 45.

I claim:

1. In a strand packaging apparatus, a plurality of driven belts superimposed one above the other and of a width substantially the axial length of the packages to be wound, a plurality of rows of rotatably mounted yarn packages positioned one above the other in step formation, resilient means to urge each of the packages of a row into engagement with one of said belts to cause the belts to engage the surface of the packages to drive the same, a plurality of rows of guides for directing the strands to the packages, and means for traversing said guides, certain of said rows of guides moving upwardly as certain other of said rows of guides move downwardly.

2. In a strand packaging apparatus, a plurality of driven belts superimposed one above the other and of a width substantially the axial length of the packages to be wound, a plurality of rows of rotatably mounted yarn packages positioned one above the other in step formation, resilient means to urge each row of said packages into engagement with one of said belts to cause the belts to engage the surface of the packages to drive the same, a plurality of rows of guides for directing the strands to the package, and means for traversing said guides, certain of said rows of guides moving upwardly as certain other of said rows of guides move downwardly, said rows being equal in number and rows of guides being arranged in balanced relation to move in opposite directions.

3. In a strand packaging apparatus, a plurality of driven belts superimposed one above the other and of a width substantially the axial length of the packages to be wound, a plurality of rows of rotatably mounted yarn packages positioned one above the other in step formation, resilient means to urge each of the packages of a row into en-

gagement with one of said belts to cause the belts to engage the surface of the packages to drive the same, a plurality of rows of guides for directing the strands to the packages, and cam means for traversing said guides, certain of said rows of guides moving upwardly as certain other of said rows of guides move downwardly.

4. In a strand packaging apparatus a plurality of driven belts superimposed one above the other and of a width substantially the axial length of the packages to be wound, a plurality of rows of rotatably mounted yarn packages positioned one above the other in step formation, resilient means to urge each row of said packages into engagement with one of said belts to cause the belts to engage the surface of the packages to drive the same, a plurality of rows of guides for directing the strands to the package, and cam means for traversing said guides, certain of said rows of guides moving upwardly as certain other of said rows of guides move downwardly, said rows being equal in number and rows of guides being arranged in balanced relation to move in opposite directions.

5. In a strand packaging apparatus, a plurality of driven belts superimposed one above the other, a plurality of rows of rotatably mounted yarn packages positioned one above the other in stepped formation and rotatable about vertical disposed axes, resilient means to urge each of the packages of a row into engagement with one of said belts to cause the belts to engage the surface of the packages to drive the same, a plurality of rows of guides for directing the strands to the packages, and means for traversing said guides, certain of said rows of guides moving upwardly as certain other of said rows of guides move downwardly.

ALBERT E. WINSLOW.
